5 Claims. (Cl. 102—39)

1

The present invention relates to a new or modified construction of electrically ignitable power gas generating blank cartridges such as are suitable for the generation of gases under pressure in the actuation of mechanical devices, for instance internal combustion engine starter cartridges. In particular the invention relates to an improved or modified method of assembling electrically ignitable power gas generating blank cartridges provided with certain kindling elements, to which reference will be made hereinunder, whereby the danger of premature ignition taking place during the loading of the cartridge is minimised.

The combustible gas producing charges in power gas generating blank cartridges usually consist mainly of smokeless powder forms of considerably large grain sizes that cannot be directly ignited by the electric fuzehead employed as electrical ignition means for the cartridges. More generally it may be stated that it is impracticable to employ for any substantial portion of the combustible charge a combustible material of such form or composition as to be easily ignited directly from the electric fuzehead, since otherwise the rate of combustion of such material would become excessive as the pressure increased, so that the rate of pressure generation would become sufficient to damage the mechanism it is required to operate. A small quantity of a composition directly ignitable by the electric fuzehead is therefore used as an intermediate kindling charge, and it is frequently necessary to employ a gas producing charge comprising more than one portion of differing forms or compositions in successive ignition relationship with said intermediate kindling charge and with one another. For instance the combustible gas producing charge for an engine starter cartridge whereof the contents are intended to be ejected in flaming condition from the cartridge case frequently comprises smokeless powder pellets of two differing sizes or compositions, one of which is less easily extinguished on ejection, or more easily ignited, than the other, as well as an intermediate kindling composition directly ignitable by the electric fuzehead.

In practice power gas generating blank cartridges frequently include for kindling purposes in the proximity of a fuzehead at the base of the cartridge a disc or cup of combustible material extending across the cartridge case and having a powder coating capable of direct ignition from the fuzehead, a plurality of powder grains capable of being ignited from said coating being hap-

2

hazardly disposed around the fuzehead and the remainder of the combustible charge being situated on the distal side of the partition. Hitherto it has been the practice to support the disc or cup bearing the coating directly ignitable by the fuzehead, for instance a Celluloid disc or cup coated with black powder, on the side next to the fuzehead upon the haphazardly disposed grains of smokeless powder or the like surrounding the fuzehead, which is protected by an open ended sheath. In the manufacture of such cartridges premature ignitions have sometimes been occasioned by friction occurring between the powder coating on the cup or disc against the exposed end of the electric fuzehead under the pressure employed in loading the cartridge.

According to the present invention, in the construction of electrically ignitable power gas generating blank cartridges of the kind wherein there is provided in the proximity of an exposed portion of an electric fuzehead at the cartridge base a partition of combustible material extending across the cartridge and bearing in its proximal side a powder coating capable of direct ignition from said fuzehead and of igniting a portion of the combustible charge disposed around said fuzehead, the said partition is supported clear of the fuzehead by means of a tubular spacing member made of combustible material resting on said base.

The tubular spacing member may advantageously be made of smokeless powder of Celluloid and may take the form of a cylindrical annulus of outer diameter slightly less than the internal diameter of the cartridge case. It will be understood that the wall of the tubular spacing member is thin enough to allow of the haphazard disposition of grains of smokeless powder or the like around the fuzehead, which is desirably protected by means of an open-ended tubular sheath, in the space between the base of the cartridge and the coated side of the partition in direct ignition relationship with the fuzehead. The length of the tubular spacing member is sufficient to ensure that even under loading pressure conditions the powder coated partition will nowhere touch the exposed portion of the fuzehead, nor compress any solid particles against it.

In loading the cartridge, the tubular spacing member may be inserted into the base of the cartridge case already containing the electric fuzehead provided with its open-ended protecting sheath, the kindling powder grains may then be introduced as by pouring or running into the cartridge case in quantity insufficient to extend

as far as the end of the tubular spacing member. The powder coated partition may then be seated on the end of the tubular spacing member with the powder coated surface facing the exposed end of the fuzehead. The remainder of the combustible charge may then be loaded on the distal side of the partition and the end of the cartridge case turned over a terminal disc of Celluloid of other combustible material in known manner.

The invention is further illustrated in the diagrammatic drawing accompanying the specification, which represents a longitudinal axial section of a power gas generating blank cartridge made in accordance with the invention.

In the diagrammatic drawing, 1 is a metal cartridge base having a central perforation 8. 2 and 4 are base wads of insulating material. 3 is a paper cartridge case wall. 11 is an electric fuzehead of which one of the terminal leading strips 9 is earthed to the metal cartridge base 1 while the other wholly insulated with wads 2 and 4 is exposed as a live terminal at the aperture 8. 13 is a Celluloid ring and 12 is a piece of rubber tubing. 6 is a Celluloid cup bearing a coating 7 of black powder attached to it. 5 are haphazardly disposed smokeless powder pellets. The powder coating 7 is capable of direct ignition from the fuzehead 11 and the pellets 5 are capable of direct ignition from the powder coating 7. 10 is a further layer of smokeless powder pellets similar to the pellets 5. 14 is a longitudinal perforated cylindrical rod of a smokeless powder composition and 15 is a Celluloid disc.

We claim:

1. An electrically ignitable power gas generating blank cartridge of the kind wherein there is provided in the proximity of an exposed portion of an electric fuzehead at the cartridge base a partition of combustible material extending across the cartridge and bearing on its proximal side a powder coating capable of direct ignition from said fuzehead and of igniting a portion of

a combustible charge disposed around said fuzehead having included therein a tubular spacing member made of combustible material resting on said base and supporting the said partition clear of the fuzehead.

- 5 2. An electrically ignitable power gas generating blank cartridge as claimed in claim 1 wherein the tubular spacing member is made of smokeless powder.
- 10 3. An electrically ignitable power gas generating blank cartridge as claimed in claim 1 wherein the tubular spacing member is made of Celluloid.
- 15 4. An electrically ignitable power gas generating blank cartridge as claimed in claim 1 wherein the tubular spacing member is in the form of a cylindrical annulus of outer diameter slightly less than the internal diameter of the cartridge case.
- 20 5. An electrically ignitable power gas generating blank cartridge as claimed in claim 1 wherein the fuzehead is protected by means of an open ended tubular sheath in the space between the base of the cartridge and the coated side of the partition.
